MACHINE FOR GRINDING THE ENDS OF
COTTON GIN RIBSJoseph Behle, Dallas, Tex., assignor to The
Murray Company, Dallas, Tex., a corporation
of Texas

Application April 26, 1929. Serial No. 358,334

6 Claims. (Cl. 51—89)

This invention relates to new and useful improvements in machines for grinding the ends of cotton gin ribs.

One object of the invention is to provide a machine whereby the ends of cotton gin ribs are automatically ground and the ribs made of uniform length.

A further object of the invention is to provide means for gripping the ribs and carrying them between grinding elements and then automatically releasing the ribs after the ends of the same have been ground.

A further object of the invention is to provide means for adjusting the grinding elements whereby they may be constantly maintained at a given distance so as to assure the grinding of all ribs to the same length.

A construction designed to carry out the invention will be hereinafter described together with other features of the invention.

The invention will be more readily understood from a reading of the following specification and by reference to the accompanying drawings in which an example of the invention is shown, and wherein:

Fig. 1 is a front elevation of a machine constructed in accordance with the invention.

Fig. 2 is a detail of the drive belt tightening device,

Fig. 3 is a side elevation of the machine,

Fig. 4 is a detail of the grinder adjustment,

Figs. 5 and 6 are sectional views of the rib carrying drum,

Fig. 7 is a reduced plan view of the machine,

Fig. 8 is an enlarged vertical sectional view showing the drum driving means,

Fig. 9 is an enlarged view of the drum and its driving means partly in section and partly in elevation,

Fig. 10 is a plan view of the rib stabilizer, and

Fig. 11 is a side elevation of the same.

In the drawings the numeral 10 designates an upright frame having a lintel 11 at its top. This frame is preferably formed of metal and channels may be used for this purpose. A bed 12 is mounted in the frame and a base 13 is secured on said bed. At each side of the base standards 14 are secured.

Circular carriers or heads 15 and 16, respectively, are each provided with central collars 17 (Figs. 5 and 9), which are suitably fastened upon a shaft 18 journaled in the upper ends of the standards 14. For revolving the shaft, a large worm gear 19 is fastened thereon, as is best shown in Figs. 8 and 9. This worm wheel is driven by a

worm screw 20 mounted upon a counter shaft 21 supported in bearing brackets 22 carried by the base 13, as is best shown in Fig. 8. The shaft 21 is driven by a worm wheel 23 which meshes with a worm screw 24 mounted on a drive shaft 25 suitably supported in the base 13. The drive shaft has a fast pulley 26 and a loose pulley 27 for receiving a suitable drive belt (not shown).

The carriers 15 and 16 are substantially alike except that the periphery of the carrier 16 is inclined to receive the foot B of the rib A, while the surface of the carrier 15 is not inclined. The carrier 15 has overhanging stop brackets 28 fixed thereon and the feet C of the ribs are engaged under these brackets and held therein by peripheral lugs 29. The carrier 16 also has the lugs 29.

Each carrier is provided with radially sliding plungers 30 having hooks 31 on their outer ends (Figs. 5 and 6), which coact with the lugs 29 to hold the ribs on the carriers. Each standard 14 carries a circular shoe or disk 32 around which one of the carriers revolves. Each plunger has a roller 33 journaled on its inner end and travelling on the shoe. On each plunger a coiled spring 34 is confined between the roller and the rim of the carrier acting to force the plunger inwardly and thus holding the roller on the surface of the shoe.

Each shoe is provided with opposite cams 35 and when the rollers ride upon these cams the plungers are displaced outwardly, as is indicated in Fig. 6. One of the cams 35 is located on the front side and functions to displace the plungers outwardly so that the ribs may be placed in position in the brackets 28 and supported by the pins 29. As the carriers revolve the rollers 33 drop off of the front cams, whereby the springs 34 cause the hooks 31 to clamp the ribs in position.

The rear cams 35 act to displace the plungers 30 outwardly so that the ribs may be discharged from the carriers upon engaging the inclined slide 36 at the rear of the machine, as is shown in Figs. 7 and 8. It will be seen that the operator merely has to place the ribs on the carriers and the rest of the operation is automatic.

For grinding the ends of the feet B and C of the ribs, grinding wheels 37 of carborundum, or any other suitable material, are mounted adjacent each carrier. Each wheel is journaled in a guard housing 38 upon an arbor 39. Each arbor is mounted in a pair of bearing boxes 40 fastened on a yoke 41 hinged on a pin 42 carried by the standards 14.

The yokes are held in position and adjusted

by means of screws 43, one of which is threaded into each yoke, as is shown in Fig. 4, and extending outwardly and loosely through an arm 44 projecting from the standard 14. Each screw 5 has an adjusting wheel 45 fastened on its outer end and carries a locking wheel 46, the hub of which is adapted to engage the arm 44 and lock the yoke 41 in position. By adjusting and fastening the yokes the grinding wheels 37, which 10 are at right angles to the carriers, are held in proper position and are correctly spaced to grind the ends of the ribs and thus gage each rib as to length.

The grinding wheels are separately driven and 15 each arbor has mounted thereon a pulley 47 driven by a belt 48, which in turn is driven by a pulley 49 mounted on the armature shaft of an electric motor 50. Each electric motor is mounted on a swing base 51 pivoted at one end to a 20 base plate 52 secured on the lintel 11 of the frame 10. The opposite end of each swing base 51 is supported on the upper end of a vertical adjusting screw 53 threaded in a boss 54 carried by the base plate 52 and depending through the 25 lintel 11, as is best shown in Fig. 2. Each screw 53 has a hand wheel 55 for adjusting the screw, whereby the base 51 may be raised or lowered to tighten or loosen the belt.

Between the carriers a substantially semi-circular hood 56 has its rear end supported on the 30 slide 36 and its front end carried by a door 57 which is supported on the base 13. The parts 36, 56 and 57 enclose the carrier driving mechanism and also close the space between the carriers. When the feet B and C of a rib pass 35 between the grinding wheels 37 the rib is supported substantially vertically over the axle 18. The rib is held in position by the coiled spring 34, but additional supporting means is provided for 40 the rib while its ends are being ground. This supporting means includes a wing 58 journaled at each end in ears 59 carried by the hood 56. The wing has a short lever 60 extending from its bottom through a slot 61 in the hood 56, as is best shown in Figs. 10 and 11. A coiled spring 62 connected to the lower end of the lever is attached to a lug 63 at the rear of the hood and within the same so as to swing the wing forwardly or toward the operator.

The wing is provided at one end with a spring-pressed hinged finger 64 carrying a cam tip 65. The tip 65 is normally held in the path of the rib A and as said rib is moved upwardly by the carriers the rib engages the tip and swings the wing 65 to an upright position against the tension of the spring 62, whereby the rib is supported as its ends are acted upon by the grinding wheels 37. After the grinding operation the rib rides off of the tip and the spring 62 returns the wing to its normal position.

It will be seen that the operator merely has to engage the feet C of the ribs under the brackets 28 so that the feet B and C rest on the lugs 29.

65

70

75

He will hold each rib in position until the rollers 33 of its plunger 30 ride off the front cams 35, after which the rib is automatically operated upon. After passing between the grinding wheels 37 the rib is released by the rear cams 35 and discharge down the slide 36, as has been hereinbefore described. The ribs discharged from the slide 36 may be suitably taken to the next machine to carry out the next step in the grinding operation.

80 Various changes in the size and shape of the different parts, as well as modifications and alterations, may be made within the scope of the appended claims.

85 What I claim is:

1. In a gin rib grinding machine, a pair of 90 grinding elements for grinding the ends of a gin rib, means for carrying a rib between said grinding elements for grinding its ends, and a rib support located in the path of a rib to be actuated by the rib into supporting position during the grinding operation.

2. In a gin rib grinding machine, a support, a carrier mounted to revolve on said support, radially movable plungers mounted on the carrier, 100 cams engaged by the plungers to displace the plungers, springs for returning the plungers, hooks on the plungers co-acting with carrier for holding a rib thereon, and means for grinding the ends of a rib held on the carrier by the hooks.

3. In a gin rib grinding machine, a support, a carrier mounted to revolve on said support, radially movable plungers mounted on the carriers, 110 cams engaged by the plungers to displace the plungers, springs for returning the plungers, hooks on the plungers co-acting with the carrier for holding a rib thereon, means for grinding the ends of a rib held on the carrier by the hooks, and stationary means on the carrier for positioning the ribs thereon.

4. In a gin rib grinding machine, a pair of 115 grinding elements, a pair of circular carriers of unequal diameters having means for gripping the feet of a gin rib for supporting said rib and for carrying said rib between said grinding elements.

5. A gin rib grinding machine as set forth in 120 claim 4, with means for adjusting the grinding elements to gage the length to which each rib is ground, and means for actuating the gripping means for discharging a rib from the carriers.

6. In a gin rib grinding machine, a pair of 125 grinding wheels, a drum having a pair of rotatable carriers at opposite ends of said drum, means on the carriers constructed for gripping the feet of a gin rib to carry the latter between the peripheries of the grinding wheels, and means for discharging the rib from the carriers, with a rib support on the drum in the path of the rib to be actuated by the rib into supporting position during the grinding operation, and means for adjusting the grinding elements toward and from the carrier.

JOSEPH BEHLE.
